UNITED STATES PATENT OFFICE.

GEORGE G. BOWEN, CHARLEY A. DULEY, AND ROBERT B. ROSS, OF IVAN, TEXAS.

FISHING TOOL FOR DEEP WELLS.

Application filed November 4, 1921. Serial No. 512,857.

To all whom it may concern:

Be it known that we, GEORGE G. BOWEN, CHARLEY A. DULEY, and ROBERT B. Ross, citizens of the United States, residing at 5 Ivan, in the county of Stephens and State of Texas, have invented certain new and useful Improvements in Fishing Tools for Deep Wells, of which the following is a specification.

10 The object of this invention is to provide a simple, inexpensive and efficient tool by the use of which other tools, nuts or other objects which may have dropped to the bottom of a well may be easily found and re-
 15 claimed. The invention seeks to provide a tool in which a plurality of object-engaging members will be held separated while the tool is being lowered into the well but will be instantly released and caused to positively
 20 and effectually clamp the object when the bottom of the well has been reached so that, upon withdrawal of the tool, the lost object will be lifted to the surface. One embodiment of our invention is illustrated in the
 25 accompanying drawing and will be herein-
 after fully set forth.

In the drawings—

Figure 1 is a longitudinal section of our improved tool;
 30 Fig. 2 is a side elevation of the same partly broken away;
 Fig. 3 is a detail perspective view of one of the slips;
 Fig. 4 is a detail perspective view of the
 35 slip-controlling head.

In carrying out our invention, we employ a socket 1 which is a cylindrical body having a closed upper end 2 and an open lower end 3. the inner surface of the socket at the lower
 40 end thereof being flared to impart a bowl-like form thereto. The socket is provided externally with a plurality of longitudinal grooves 4 which form water courses to permit the escape of oil, water or other liquid
 45 when the tool is being withdrawn so that its upward progress will not be unduly retarded, and the greatest external diameter of the socket will be such that the socket will fit closely but slidably within the well in which
 50 it is to be used, it being our intention, in the commercial exploitation of the invention, to provide the sockets in various sizes corresponding to the standard diameters of wells. Arranged alternately with the grooves 4,
 55 openings 5 are formed through the wall of the socket and these openings provide seats

for the offsets 6 of the slips 7. The offsets, as shown most clearly in Fig. 1, do not entirely fill the openings 5 but are capable of pivotal movement therein and are retained 60 within the said openings by pivot pins 8 inserted through the ribs or projecting portions of the socket occurring between the longitudinal grooves 4 and through openings 9 in the offsets, as will be readily understood 65 upon reference to Figs. 1 and 2. The portions of the slips below the offset 6 are tapered downwardly and at their lower extremities on their inner sides are provided with shoulders or teeth 10 to more effectually engage the object which is to be withdrawn from the well. The slips are arranged to play in longitudinal grooves 11 formed in the inner surface of the socket 1 and the portions of the slips above the offset 6 are disposed at a slight angle to the lower portions thereof, as shown. The upper portions 12 of the slips are also out of alignment with the lower portions so that shoulders 13 are provided upon which the controlling head 14 may rest. The said head 14 is a wedge-shaped or downwardly flared body having slightly flattened surfaces 15 to engage the inner faces of the upper portions 12 of the slips and from the upper end 85 of the said head, a shank 16 extends through the upper end 2 of the socket to engage in and be secured to the coupling 17 which may be suspended upon the end of a cable or may form the end of a jarring rod or other supporting instrumentality. In the drawing, the coupling 17 is shown as terminating in a threaded pin 17' to be engaged in a box on the lower end of the fishing rod. The shank 16 is of angular cross section through 90 that portion which passes through the top of the socket and above the said angular portion is of circular cross section and threaded, as indicated at 18, whereby it may be readily secured in the lower end of the coupling. 95

When the tool is to be lowered in a well, the lower ends of the slips 7 are held apart, as indicated in full lines in Fig. 1, by fitting frangible pins 19 between the opposed slips so that the lower ends of the slips will be seated in the grooves 11. The tool is then suspended by the coupling 17 on the fishing rod and is permitted to drop to the bottom of the well through the force of gravity or, in some instances, by force applied to the fishing rod. The head 14 during the descent of the tool will be lowered relative 100
 105
 110

to the slips so that it will rest upon the shoulders 13 and will permit the upper ends of the slips to swing inwardly. When the tool reaches the bottom of the well or the 5 object which is to be withdrawn, the impact upon the object will break the pins 19, which may be thin pieces of light wood or other material, so that the lower ends of the slips may then swing inwardly and engage 10 the object, as indicated by dotted lines in Fig. 1. If a lifting force be then applied, the head 14 will be drawn upwardly and by reason of its flared or wedge-shaped construction will spread the upper ends of the 15 slips, thereby forcing the lower ends of the same into positive gripping engagement with the object. The gripping action of the slips upon the object which is to be withdrawn from the well will be increased 20 as the tool moves upwardly owing to the fact that the entire weight of the socket and the slips will be carried by the head and as the said weight tends to move the sockets and the slips relatively downward, the 25 flared or wedge shape of the head will bind it against the upper ends of the slips forcing them outwardly and positively holding them against release.

Our improved tool is very simple in the 30 construction and arrangement of its parts and is not apt to get out of order, while it may be easily operated and will be found highly efficient for the purpose for which it is designed. The external grooves in the 35 socket will provide for the escape of water or other liquid which may be in the well above the tool and at the same time will reduce the surface of the tool in contact with the wall of the well and thereby mini- 40 mize the frictional resistance and wear. As the socket will be made of an external diameter approximately equal to the internal diameter of the well, the tool will be held positively to the center of the well and will, 45 therefore, be guided with certainty over the object which is to be withdrawn and cannot pass to the side of the same so as to miss it.

Having thus described the invention, what is claimed as new is:

50 1. A tool for the purpose set forth comprising a socket provided with external longitudinal grooves, a plurality of slips pivotally

mounted within the socket, and means for holding the lower ends of the slips spread during descent of the socket and permitting the same to close and remain closed during ascent of the socket. 65

2. A fishing tool for wells comprising a socket having a lower open end and having openings through its wall intermediate 70 its ends, a plurality of slips disposed within the socket and provided with offsets pivotally seated within the openings in the wall of the socket, a downwardly flared head arranged between the upper ends of the slips and having relative movement through the upper end of the socket, and means above the socket connected with said head for suspending the tool. 65

3. A fishing tool for wells comprising a socket having an open lower end and provided with internal longitudinal grooves, a plurality of slips each seating in one of 75 said internal grooves and pivotally fitted in the wall of the socket, frangible means for holding the lower ends of the slips expanded, a relatively movable head arranged between the upper ends of the slips and adapted to spread the same upon release of 80 the said frangible means, and a suspending device connected with said head. 70

4. A fishing tool for wells comprising a socket having an open lower end, a plurality of slips pivotally fitted in the wall 85 of the socket and having tapered lower ends, inwardly projecting shoulders on said slips above the pivotal points of the same, a downwardly flared head disposed within the socket and between the upper ends of 90 the slips and engaging said slips to spread the same upon upward movement of the head, the head normally resting on the inwardly projecting shoulders whereby to spread the lower ends of the slips during 95 downward movement of the tool, a shank extending from the head through the upper end of the socket, and a suspending member secured on the upper end of said shank. 100

In testimony whereof we affix our signatures.

GEORGE G. BOWEN. [L.S.]
CHARLEY A. DULEY.
ROBERT B. ROSS.
